(57) **CLAIM**

The ornamental design for a false eyelash box, as shown and described.

DESCRIPTION

FIG. 1 is a front elevational view of a false eyelash box showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view of a false eyelash box showing my new design;

FIG. 8 is another perspective view thereof;

FIG. 9 a perspective view showing that a false eyelash box is in a open status; and,

FIG. 10 a perspective view showing that the false eyelash box is in another open status.

The broken lines in the figures are for the purposes of illustrating portions of the false eyelash box, which form no part of the claimed design.

1 Claim, 10 Drawing Sheets
